UNITED STATES PATENT OFFICE.

ROY S. SHARPNACK, OF DILLINER, PENNSYLVANIA.

CAR FEEDER.

Application filed June 21, 1924. Serial No. 721,490.

To all whom it may concern:

Be it known that I, ROY S. SHARPNACK, a citizen of the United States, and resident of Dilliner, in the county of Greene and State of Pennsylvania, have invented a new and useful Improvement in Car Feeders; and I do hereby declare the following to be a full, clear, and exact description thereof.

My invention relates to car feeders, and particularly to means for positively controlling movement of cars past a point of loading such as a coal tipple.

My invention has for its object the provision of means, whereby cars or other vehicles may be advanced past a loading station, while at the same time provision is made to insure that the car will not advance farther than desired.

One form which my invention may take is shown in the accompanying drawing, wherein Fig. 1 is a view showing one manner in which my invention may be employed in connection with the loading of cars at a tipple; Fig. 2 is a fragmentary view of a portion of the apparatus of Fig. 1, on an enlarged scale; and Fig. 3 is a view, on an enlarged scale, of a portion of the operating mechanism.

In order to clearly describe my invention I have shown an open-top car 4 that is to be moved to the right along railroad tracks 5, beneath a chute 6 of a coal tipple 7. According to the usual practice, the track 5 is inclined slightly so that under favorable conditions the car will advance to the right under the action of gravity, upon release of the brakes, not shown, the brakes being intermittently released as the car is being loaded so that the load is distributed throughout the length of the car.

However, at times the cars will not move readily, owing to the presence of loose coal on the track, or faulty lubrication, in which case it has been customary to advance the car with pinch bars. Whether the car is caused to advance simply by releasing the brakes or by pinch bars, there is always danger of it advancing a too great distance before the brakes can be applied.

My invention comprises means for effectively controlling the movement of the car by power means, which is under control of an operator, for advancing the car, which same means serves also to retard the movement of the car upon release of the motive force.

The apparatus comprises a bracket member 8 bolted to an upright 9 of the tipple 7 and provided with bearings for a shaft 10 upon which shaft are rigidly secured the worm gear 11 and a winding drum 12.

I mount a shaft 13 at right angles to the shaft 10. A worm 14, meshing with the gear wheel 11, is secured to the shaft 13 and a crank 15 is provided for rotating the shafts 13 and 10. Instead of the crank 15 I may provide a motor for rotating the shaft 13 under control of the operator or load trimmer who stands on the platform 16.

Beneath the drum 12 I mount a pair of sheaves 17, only one of which is shown in the drawing. The sheave 17 is supported by a bracket 18 that is in turn yieldingly supported upon an upright 9 by a bolt 19 and a spring 20 which is interposed between the upright 9 and the fixed washer 21 on the bolt 19. At a point remote from the tipple 7 I provide an anchoring post 22 through which extends a swivel bolt 23 that is provided at its outer end with a fixed washer 24 that serves as a seat for one end of a spring 25, the other end of which seats against the post 22. A sheave or pulley 26 is pivotally supported by the bolt 23.

A cable 27 is wound around the drum 12 a plurality of times from opposite sides thereof, so that as the drum is rotated the amount of cable wound thereon will be equal to the amount paid out. Each of the reversely wound portions of the cable may pass around the guiding sheaves 17 and around the end sheave 26.

To each side of the pulley 26 I mount one or more loosely supported couplings 27^a, each of which comprises a hook supported by links from a chain link 28, the chain link 28 being connected through links 29 and pins 30 to a sleeve 31 that is in turn connected to the cable 27 by a hook bolt 32 and a spring 33 seated between the one end of the sleeve and a washer 34 on the inner end of the hook bolt 32.

In Fig. 1 a car is shown in loading position and connected to one of the hooks 27^a, while the other hook 27^a is in position to be connected to an empty car, not shown. The car 4 is advanced by means of the worm drive 14—11, upon rotation of the crank 15 in the proper direction. Should the car tend to move without the appli-

cation of any force to the handle 15, such movement will be retarded by reason of the fact that the worm drive will act as a brake. Thus the movement of the car can be definitely controlled regardless of whether it moves under its own momentum or requires the application of power.

When the car 4 has been advanced completely beneath the chute 6, the coupling 27^a is disengaged therefrom and the other coupling 27^a is connected to an empty car, whereupon the crank 15 is turned in the reverse direction, to advance the second named coupling 27^a with the car. During this advance movement, that coupling 27^a which has just been disengaged from the car 4 is of course caused to be retracted to a position for engagement with another empty car. It will be seen that the cable 27 is substantially continuous, being interrupted only by the insertion of the couplings 27^a, but it will be understood that it may be divided and its ends oppositely wound upon the drum 12.

By my invention I provide a means whereby the car is definitely under control of the operator or load trimmer, and he need not leave his station to either operate the brakes of the car or to use a pinch bar or other means to advance it. Further, no delay is encountered through call of assistance to move a car which fails to advance upon release of the brakes.

It will be understood that but a single coupling 27^a is required, or that more than two couplings may be employed. The placing of couplings at each side of the sheave 26 results in a saving of time to the operator, as during advancement of one car the

other coupling is moving rearwardly in position to advance another car. Further it is not essential that the cable be wound around the drum a plurality of times, if means be provided for preventing slipping thereof.

Various modifications in detail and general arrangement may be made without departing from the spirit and scope of the invention as defined in the accompanying claims.

I claim as my invention:

1. Car feeding apparatus comprising a winding drum, a cable having portions thereof reversely wound on said drum, a fixedly mounted sheave around which the cable passes, a coupling member secured to said cable intermediate the said drum and sheave, and a worm drive for said drum, to serve both as an advancing and as a retarding device.

2. Car feeding apparatus comprising a supporting bracket adapted to be mounted above a track along which cars are to be moved, a winding drum mounted on said support, a guiding sheave disposed at a point beneath said support, a guiding sheave horizontally removed from said first-named sheave and adjacent to the track along which cars are to be moved, a cable extending around said sheaves and reversely wound on said drum, a coupling member secured to said cable at a point between said sheaves, and a worm drive for said drum, serving both as an advancing and a retarding medium for cars being moved.

In testimony whereof I, the said Roy S. SHARPNACK, have hereunto set my hand.

ROY S. SHARPNACK.
